UNITED STATES PATENT OFFICE.

CHARLES H. STONEBRIDGE, OF NEW YORK, N. Y.

TENT.

988,400.

Specification of Letters Patent. Patented Apr. 4, 1911.

Application filed July 3, 1909. Serial No. 505,795.

To all whom it may concern:

Be it known that I, CHARLES H. STONEBRIDGE, a citizen of the United States, and residing at New York, in the county of New York and State of New York, have invented certain new and useful Improvements in Tents, of which the following is a specification, such as will enable those skilled in the art to which it appertains to make and use the same.

This invention relates to tents; and the object thereof is to provide an improved device of this class which may be compactly folded or packed together into the smallest possible space for transportation or shipment purposes, and which may be quickly, easily and conveniently set up for use whenever desired and as quickly, easily and conveniently taken down and folded together or packed for transportation or shipment purposes, and which will also possess the least possible weight; and with these and other objects in view the invention consists in a tent constructed as hereinafter described and claimed.

The invention is fully disclosed in the following specification, of which the accompanying drawings form a part, in which the separate parts of my improvement are designated by suitable reference characters in each of the views, and in which;—

Figure 1 is a perspective view of my improved tent set up ready for use, Fig. 2 a sectional side view thereof, Fig. 3 a sectional view of the top of a tubular telescopic center pole which I employ and showing a part of the roof construction of the tent connected therewith, Fig. 4 a sectional view showing the tubular telescopic center pole of my improved tent with the parts of the pole telescoped together and reinforcing and supporting devices forming a part of the tent construction placed in the telescoped parts of the center pole, Fig. 5 a sectional plan view of the tent shown in Figs. 1 and 2, the section being through the eaves part of the tent on the line 5—5 of Fig. 2, Fig. 6 a sectional view similar to Fig. 5, but showing only a part of the eaves construction and showing the same on an enlarged scale, Fig. 7 a section on the line 7—7 of Fig. 6, Fig. 8 a view similar to Fig. 6 but showing a modification, Fig. 9 another view similar to Fig. 6 and showing another modification, but showing only a part of the construction shown in Fig. 6, Fig. 10 a partial section on

the line 10—10 of Fig. 1, or on the line 10—10 of Fig. 12, Fig. 11 a view similar to Fig. 10 but showing a modification, Fig. 12 a detail view showing means for reinforcing the corners of the body portion of the canvas body of the tent and providing the same with reinforcing cords or stays and showing also a means for connecting the tent with ground stakes for holding the tent in position, and;—Fig. 13 a side view showing a modified form of tent in which only one-half of the regular center pole is employed, and showing the bottom body portion of the tent rolled up and part of said body portion being broken away.

In the practice of my invention I provide a tent body *a* composed of canvas and comprising a bottom portion *a*² and roof portion *a*³, the connection between said bottom portion and roof portion forming the eaves *a*⁴, and said tent is provided with a front vestibule *a*⁵ comprising side members *a*⁶ and a top member *a*⁷ within which are flaps *a*⁸ which constitute the door proper of the tent, 80 and which may be secured in a closed position in any desired manner, and which may also be opened when desired to permit of ingress to and egress from the tent. I also employ a tubular telescopic center pole *b* comprising a bottom portion *b*² and top portion *b*³ adapted to be telescoped into the bottom portion *b*². The bottom portion *b*² of the center pole is provided at its lower end with a threaded cap *b*⁴ adapted to rest on 90 the ground or to be secured to the ground in any desired manner, and the top part of the bottom portion *b*² is reduced in size as shown at *b*⁵ in Figs. 2 and 4, the reduced portion forming an inner annular shoulder *b*⁶.

The top portion *b*³ of the center pole is provided with a reduced extension *b*⁷ adapted to enter the reduced part *b*⁵ of the bottom portion *b*² of said pole, and said top portion 100 is also closed at its upper end as shown at *b*⁸ in Fig. 4, and provided with a cap *c* comprising a tubular part *c*² and top plate *c*³ as shown in Fig. 3.

The cap *c* of the top portion *b*³ of the center pole is, in practice, secured to the roof part *a*³ of the canvas body portion *a* of the tent as clearly shown in Figs. 2 and 3, and for this purpose the plate *c*³ of the cap *c* is provided at its edges with holes *c*⁴, and 110 strong straps *c*⁵ are passed therethrough and secured to the roof part *a*³ of the canvas

body portion of the tent. The top plate c^3 of the cap c is also provided centrally and transversely of the bottom side thereof with a rod c^6 which is secured thereto in any desired manner and which fits in corresponding recesses c^7 formed in the top of the opposite sides of the top part b^3 of the center pole, and in practice I also pass through the tubular portion c^2 of the cap c and through the top part b^3 of the center pole a pin c^8 , and this construction prevents the cap c from turning on the center pole or the top part thereof.

The roof part a^3 of the canvas body of the tent is connected with the bottom part a^2 at d to form the eaves a^4 , and this connection is made by a folded seam such as is shown in Fig. 11. The roof part a^3 of the flexible or canvas body of the tent is also composed of separate triangular-shaped parts d^2 which are all of the same size and the wider ends of which are at the eaves of the tent connected by seams d^3 similar to the seam shown in Fig. 11, the object of the seams d and d^3 being to render the connection between the parts of the roof construction a^3 and the eaves a^4 strong and durable and to reinforce said parts where they are connected.

The bottom part a^2 of the flexible canvas body portion of the tent is also composed of separate corner parts e and side parts e^2 connected at e^3 by seams similar to the seams d and d^3 and similar to that shown in Fig. 11, but these seams e^3 may be made as shown in Fig. 10 if desired, in which the separate parts of the bottom part a^2 of the body of the tent are reinforced where connected by a strip or strips e^4 secured thereto, and a cord e^5 is held in place by said strip or strips and secured thereto and to the bottom of the body portion, and when the form of construction shown in Fig. 10 is employed the cords e^5 may serve as stay cords for securing the tent to ground stakes f .

The corner parts e of the bottom portion of the body of the tent are exactly triangular in form and the wider ends thereof are at the eaves of the tent, while the side parts e^2 of said bottom portion of the body part of the tent are tapered upwardly, the top edges of said parts at the eaves of the tent being exactly of the same length, and by reason of this construction the shape of the tent at the eaves is that of an octagon or eight sided figure, while the bottom of the tent is exactly square and this gives the greatest possible space within a tent of given dimensions and also gives to a tent constructed, as herein shown and described, the greatest possible strength when in position for use, and also facilitates the folding and packing of the separate parts as shown and described.

The ground stakes f are provided with a plurality of holes f^2 , and in practice rings

f^3 are connected therewith and the cords e^5 are passed through the ring f^3 and secured to rings f^4 secured to the inner side of the bottom of the body portion of the tent, and preferably to the reinforcing strips e^4 , and by means of these cords e^5 , the body portion of the tent may be drawn down and made perfectly tight as will be readily understood, and the bottom edge of the body part a^2 of the tent is also provided with cords f^5 which are secured thereto at f^6 and which may also be secured in the rings f^3 , and by means of this construction the bottom edge of the body part of the tent may be secured closely adjacent to the ground, or by releasing the cords f^5 the said bottom edge may be rolled up or raised for ventilation or other purposes, and this construction is also of value when it is desired to place the tent on an inclined surface or on the side of a hill, in which event the bottom of the tent may either be raised or lowered at one side as may be desired.

The parts e^2 of the bottom part a^2 of the body portion of the tent are wider and larger than the parts e and are reinforced by diagonally arranged stays, cords or similar devices g which may be secured to the stakes f to reinforce the tent and hold it in case of a storm, and the top portions of the parts e are provided with reinforcing cords g^2 which are secured to the inner side thereof and which are brought out through said parts at g^3 , and the object or use of which will be hereinafter described.

The side portions a^6 of the vestibule of the tent and the top are connected with the body of the tent as shown in Figs. 1, 2 and 5, and cords g^4 are secured to the body portion of the tent where the sides a^6 of the vestibule are connected therewith, and if desired the sides a^6 of the vestibule may be rolled up and secured in position by the cords g^4 .

Extending entirely around the body portion of the tent at the eaves thereof and preferably inside of said eaves is a reinforcing and supporting ring or band h composed of separate rods h^2 which are all of the same length and also interchangeable, and these rods are connected by tubular keepers h^3 , and said tubular keepers are preferably slightly curved, these features of construction being clearly shown in Figs. 2, 5 and 6, and the keepers h^3 are secured to the body portion of the tent at the eaves thereof by bands h^4 or in any desired manner.

In practice, the keepers h^3 are secured in place and the ends of the parts or rods h^2 of the ring or band are inserted thereinto as clearly shown in Figs. 5 and 6, and in this operation one of said keepers is preferably secured in place, a rod is inserted into one end thereof, another keeper is mounted on the opposite end of said rod and then secured in place and another rod inserted into said keeper, and this operation is proceeded

with entirely around the eaves portion of the body of the tent until the ring or band h is completed.

Instead of making the ring or band h as shown in Figs. 5 and 6 and as hereinbefore described, the rods or parts h^2 of said ring or band may be provided at one end with a keeper h^5 into which another part or rod h^2 of said ring or band is inserted as shown in Fig. 8, and when this form of construction is employed the separate parts h^2 of the ring or band h are passed through pockets or similar devices h^6 secured to the inner side of the eaves portion of the body of the tent. Another modification of this construction is shown in Fig. 9 in which the separate parts h^2 of the ring or band h are curved and connected by short straight tubular keepers h^7 secured to the eave construction 10 of the tent by flexible strips h^8 similar to the strips h^4 shown in Fig. 6 or in any desired manner.

In practice, in the operation of packing the tent for shipment or other purposes, the 25 separate parts h^2 of the ring or band h and the keepers h^3 or h^7 are placed in the top part b^2 of the center pole b , and said top part of the center pole is inserted into the bottom part b^2 thereof as shown in Fig. 4 30 and the lower end of the bottom part of the pole is closed by the cap b^4 of said pole, and the flexible body portion of the tent may be compactly rolled up and rolled around the telescoped center pole.

35 In case it is desired to make a tent particularly strong, as for instance in case of a storm or a contemplated storm, the top part b^3 only of the center pole is employed as indicated in Fig. 13, the bottom edge portion of the body part of the tent is rolled up as shown at i in said figure and the cords g^2 are employed for securing the body of the tent to the stakes f , and in this operation the bottom of the side members a^6 of the vestibule are also rolled up as shown at i^2 and cords i^3 secured to the side portions a^6 of the vestibule are employed for securing said side portions of the vestibule to the stakes f .

40 My invention is not limited to any of the 50 details for making or forming the body portion a^3 and a^2 of the tent, but the construction herein shown and described is that which I prefer, and various changes in and modifications of the various details of the 55 tent construction herein described may be made, within the scope of the appended claims, without departing from the spirit of my invention or sacrificing its advantages.

45 The top of the vestibule at the front of 60 the tent is supported by cross rods j which are inserted into pockets j^2 at the eaves portion of the body of the tent, and other pockets j^3 are secured to the top of the vestibule as clearly indicated in Fig. 5, and these rods 65 support the vestibule and in connection with

the top a^7 thereof prevent said vestibule from drooping at the top.

By employing the ring or band h at the eaves of the tent as herein shown and described, I avoid the use of all braces or similar devices connected with the center pole in any way for supporting the body of the tent including the roof a^3 and bottom portion a^2 thereof, and when the center pole is connected with the center of the roof construction as herein shown and described, the ring or band h is placed in position as shown and described and the bottom of the body portion securely connected with the stakes f , the tent will be firmly supported against 70 all possible contingency, and if at any time it is desired to do so the bottom part b^2 of the center pole may be removed and the form of tent shown in Fig. 13 may be employed. 75

Having fully described my invention, what I claim as new and desire to secure by Letters Patent, is:—

1. In a tent, a center pole and a flexible body portion consisting of a roof member 90 and a bottom member connected to form the eaves of the tent, the said body and roof members being octagonal in form at the eaves and the bottom member being square at the bottom thereof; and the eaves portion 95 of the tent being reinforced by a ring or band composed of separate substantially straight parts and connecting members having sockets in their ends adapted to receive the ends of said substantially straight parts, 100 said substantially straight parts being all of the same length and interchangeable.

2. In a tent, a body portion composed of flexible material and comprising roof and bottom parts united to form the eaves of the 105 tent, the roof and bottom parts being octagonal in form at the eaves and the bottom part being rectangular in form at the bottom thereof and a reinforcing ring or band placed at the eaves of the tent. 110

3. A tent, comprising a center pole and a body composed of flexible material and comprising a roof member and a bottom member connected to form the eaves of the tent, the bottom member being composed of four side 115 portions and four corner portions, the corner portions being triangular in form with the wider ends thereof at the eaves of the tent and the end edges of the said portions being tapered inwardly and upwardly to the eaves 120 of the tent and the top edges thereof being of the same length as the top edges of the corner portions, the roof portion of the tent being also composed of triangular pieces 125 which are eight in number and the eaves of the tent being reinforced by a ring or band consisting of separate detachably connected parts, said parts being substantially straight and being interchangeable and the lengths thereof being the same as the width of the 130

- separate parts of the roof and top portions of the body at the eaves of the tent.
4. In a tent, a center pole and a flexible body portion consisting of a roof member and a bottom member connected to form the eaves of the tent, said bottom and roof members being octagonal in form at the eaves and the bottom member being rectangular in form at the bottom thereof, and the eaves portion of the tent being reinforced by a ring or band composed of separate detachably connected parts.
5. In a tent, a center pole and a flexible body portion consisting of a roof member and a bottom member connected to form the eaves of the tent, said bottom and roof members being octagonal in form at the eaves and the bottom member being rectangular in form at the bottom thereof, and the eaves portion of the tent being reinforced by a ring or band composed of separate detachably connected parts, said parts being interchangeable, and being all of the same length.
6. A tent, comprising a center pole, and a body composed of flexible material and comprising a roof member and a bottom member connected to form the eaves of the tent, the bottom member being composed of four side portions and four corner portions, the corner portions being triangular in form with the wider ends thereof at the eaves of the tent, and the end edges of the side portions being tapered inwardly and upwardly to the eaves of the tent, and the top edges thereof being of the same length as the top edges of the corner portions, the roof portion of the tent being also composed of triangular pieces which are eight in number, and the eaves of
- the tent being reinforced by a ring or band consisting of separate detachably connected parts.
7. A tent, the body portion of which is composed of flexible material and consists of a roof portion and a body portion united to form the eaves of the tent, said roof and body portions being each composed of a plurality of parts and the tent being octagonal in form at the eaves thereof and the body portion thereof being rectangular in form at the bottom thereof and a reinforcing ring or band placed at the eaves of the tent and composed of separate detachably connected parts equaling in number the parts in the roof portion of the tent.
8. A tent, comprising a center pole and a body composed of flexible material and comprising a roof member and a bottom member connected to form the eaves of the tent, the bottom member being composed of four side portions and four corner portions, the corner portions being triangular in form with the wider ends thereof at the eaves of the tent and the end edges of the side portions being tapered inwardly and upwardly to the eaves of the tent and the top edges thereof being of the same length as the top edges of the corner portions, the roof portion of the tent being also composed of triangular pieces which are eight in number.
- In testimony that I claim the foregoing as my invention I have signed my name in presence of the subscribing witnesses this 2nd day of July, 1909.
- CHARLES H. STONEBRIDGE.
